UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A BORDER FOR SILVERWARE.

SPECIFICATION forming part of Design No. 25,938, dated August 18, 1896.

Application filed July 6, 1896. Serial No. 598,239. Term of patent 7 years.

To all whom it may concern:

Be it known that I, CHARLES OSBORNE, a citizen of the United States, residing in New York city, in the county and State of New York, have invented and produced a certain new and original Design for a Border for Silverware and Like Goods, of which the following specification, with the accompanying drawing, is a full and exact description.

10 The drawing is a face view of a short length or section of the border.

The leading feature of my design is the slender double-curved interlaced scrolls, alternating with similarly-shaped, but shorter, foliated or plumed scrolls joined to a narrow ornamental edging. At about the mid-width of the border, at short intervals, is a foliated scroll ornament in relief, and at the outer edge is a series of short single-curved scroll members arranged with their convex sides outward, touching the interwoven scrolls with their inturned ends. A panel surrounded by scrolls ornamented by a foliate edging forms a part of the border and is introduced at intervals.

25 The inner edging is marked A. It is ornamented by a molding of conventional leaves in relief and is joined by a series of slender double-curved scrolls or stems C C, each crossing the lower end of the preceding and overlapping upon the similar succeeding member. Alternating with these scrolls are correspondingly-curved, but shorter, scrolls B B, spring-

ing from the edging A and terminating near the outer end of each scroll C. The scrolls 35 B are heavier than the others and show a feather-like ornament along one side.

D D are heavy scrolls in relief, superposed upon the scrolls B at about the mid-width of the border and curving gracefully to and 40 upon the slender scrolls C.

E E are curved members springing from the ends of the plumed scrolls B and extending, convex side outward, to the next scroll C, forming a series of loops or scallops along 45 the outer edge of the border. At intervals depending in frequency on the size and shape of the article to which the border is to be applied are panels F, surrounded by heavy scrolls in relief edged with feather-like ornaments harmonizing with the plumed scrolls B.

The design produces a peculiarly-pleasing effect of lightness and grace by reason of the long sweeping curves of the principal members, relieved from attenuation by the plume 50 ornaments and the superposed heavy scrolls.

I claim—

The design for a border for silverware and like goods, herein shown and described.

In testimony that I claim the invention 60 above set forth I affix my signature in presence of two witnesses.

CHARLES OSBORNE.
